UNITED STATES PATENT OFFICE

95,911

DESIGN FOR A HOUSE LETTER BOX

Julius Kim, Cheswick, Pa.

Application March 15, 1935, Serial No. 55,883

Term of patent 3½ years

To all whom it may concern:

Be it known that I, Julius Kim, a citizen of the United States, residing at Cheswick, in the county of Allegheny and State of Pennsylvania, have invented a new, original, and ornamental Design for a House Letter Box, of which the following is a specification, reference being had to the accompanying drawing, forming part thereof.

In the drawing:

The figure is a perspective view of a house letter box, showing my new design.

I claim:

The ornamental design for a house letter box, as shown.

JULIUS KIM.
